UNITED STATES PATENT OFFICE.

CHARLES C. STEGER, OF DAYTON, OHIO.

ARCH-SUPPORTER.

1,085,507.

Specification of Letters Patent.

Patented Jan. 27, 1914.

Application filed January 9, 1913. Serial No. 740,943.

To all whom it may concern:

Be it known that I, CHARLES C. STEGER, a citizen of the United States, residing at Dayton, in the county of Montgomery and State of Ohio, have invented a new and useful Improvement in Arch-Supporters, of which the following is a specification.

This invention relates to new and useful improvements in arch supporters.

10 The object of the invention is to provide a firm, flexible and comfortable support for the arch of the foot, and it is particularly adapted for treating and protecting weak and afflicted arches and insteps.

15 My improved support is readily and easily insertible in a boot or shoe, and is so constructed that when the foot bears upon the bottom portion of the support, the side wing thereof will be forced toward the arch of 20 the foot to firmly brace and support it.

With the above and other important incidental objects in view, my invention consists of the arrangement and construction of parts set forth in the following specification 25 and particularly pointed out in the subjoined claim.

In the accompanying drawings, Figure 1 is a perspective view of my improved arch supporter. Fig. 2 is a bottom plan view 30 of the same. And Fig. 3 is a section taken on the line *a—a* of Fig. 2.

Throughout the specification and drawings, similar reference characters denote corresponding parts.

35 In a detailed description of my invention, 1 designates the heel portion of my improved arch supporter, which is preferably constructed of hard leather duly hammered to give it the desired rigidity. Ex-

40 tending forwardly from the heel portion 1, and integral therewith, is a longitudinal arched portion 2, also constructed of hard leather and being sufficiently flexible to conform to the arch of the foot. Bent up from

45 one side of the heel and longitudinal arch portions of my support, is a side or wing portion 3. This wing portion extends almost perpendicularly above the heel portion 2,

and gradually flares outwardly and downwardly as it approaches the end of the longitudinal arched portion 2.

4 designates a longitudinal relatively narrow strip of hard leather, rubber or other firm material, which is suitably secured to the bottom portion of my support to form a fulcrum, whereby, when the foot presses down upon the heel and longitudinal arched portions of my support, the wing portion 3 thereof will be forced upwardly and inwardly toward the arch of the foot to firmly brace and support it. The heel portion 1 is provided with an aperture 5 to receive a screw or other means (not shown) for fastening the supporter to the shoe if desired.

65 My improved arch supporter is simple, may be easily and economically constructed, and may be readily inserted into and removed from a boot or shoe by the wearer. When in place, it readily accommodates itself to the foot, and responds at the times it is most needed to protect and brace the arch. For example, the arch or instep must be more firmly braced and protected when a step is being taken. Accordingly, when 70 the foot bears down upon my support, the wing 3 is forced upwardly and inwardly against the arch, thereby protecting and strengthening it and at the same time affording the wearer ease and comfort when 75 walking.

As my improved arch supporter is wholly constructed of hard leather duly hammered, it will have sufficient flexibility and stability to firmly support the arch and instep 85 in all of its positions, with comfort to the wearer.

I do not wish to be limited to the details of construction and arrangement herein shown and described, but the same may be 90 varied to suit different conditions of use.

Having described my invention, I claim:

A foot arch supporter adapted to be inserted in boots and shoes, comprising a heel portion, a longitudinal arched portion integral with said heel portion, an upwardly and

outwardly flaring wing portion bent up from one side of said heel and longitudinal portions, and a longitudinal relatively narrow strip mounted beneath said heel and 5 longitudinal arched portions, approximately midway of the latter, and arranged to act as a fulcrum whereby the wing portion is forced tightly against the arch of the foot when the longitudinal arched portion of the

supporter is depressed, substantially as de- 10 scribed.

In testimony whereof I have hereunto set my hand this 6th day of January, 1913.

CHARLES C. STEGER.
